(57) **CLAIM**

The ornamental design for a pillow, as shown and described.

DESCRIPTION

FIG. 1 is a front, right, and top perspective view of a pillow, showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The short dash and long dash broken lines in the drawings illustrate stitching lines that are part of the claimed design. The evenly dashed broken lines in the drawings depict portions of the pillow that form no part of the claimed design.

1 Claim, 8 Drawing Sheets
